DISPLAY SIGN

Benton N. Reamer, Jersey City, N. J.

Application June 2, 1938, Serial No. 211,369

6 Claims. (Cl. 40—30)

The invention relates to display signs and has particularly to do with an advertising device for displaying two sets of subject matter on either outdoor or indoor signs.

Signs of this nature, particularly in outdoor locations, are expensive to install and rentals are high. It is therefore of considerable advantage to the advertiser to utilize a sign in which two aspects of his product may be shown in one sign. It is also well known that a movable sign attracts a great deal more attention from the public. Signs built in accordance with the invention have many possibilities, for instance, in one display the sign may show suitable printed matter relating to the advertised product and in the other display one or more pictures may be shown that are pertinent to the product.

Among the objects of the invention are to provide a simple, rugged and durable sign that will function efficiently with practically no attention. A further object is to provide a sign that will withstand extreme weather conditions, particularly high winds.

Other objects and advantages will become apparent as this specification proceeds. Referring to the drawings forming a part thereof and in which one embodiment of the invention is illustrated:

Fig. 1 is a front elevation, parts being broken away for clearer illustration;

Fig. 2 is a cross-sectional view taken on line 2—2 of Fig. 1; and

Fig. 3 is a fragmentary detail sectional view showing the curtain or movable sign being displayed.

Referring again to the drawings the sign and its operating mechanism are supported on suitable structural members generally indicated by the reference character 5. The structural arrangement may vary widely in formation, one requisite being that an open space 6 be maintained in the rear for purposes hereinafter described.

The structural members 5 support a housing 7 for the sign. This housing may carry suitable advertising matter and its front part is provided with an opening 8 through which the advertising matter on the upright sign proper 9 may be viewed. It will be noted the face of the sign 9 slopes slightly inwardly from top to bottom. This slope is not enough to be susceptible to the eye in viewing the sign but it plays an important function which will hereinafter be described.

The movable sign which is moved upwardly and downwardly over the fixed sign 9 so as to

uncover or cover said fixed sign comprises a curtain 10 upon which suitable advertising matter may be painted or posted. The curtain has a boom 11 secured to its front end and another boom 12 secured to its rear end.

The curtain passes over a roller 13 coextensive with the width of the curtain and having suitable bearings in the structural members 5. Idler rollers 14 may be provided to support the drum or roller 13 intermediate the bearings.

Secured to the ends of the front and back booms 11 and 12 are shock absorbing springs 15 which have their opposite ends secured to sprocket chains 16. The sprocket chains 16 are driven by sprockets 17 mounted on a shaft 18 which in turn is geared to and driven by a reversing motor 19. The sprocket chains pass over idler guide rollers 20.

The front boom 11 carries on either end guide-rollers 21 which engage tracks 22 at either end 20 of the sign. The tracks 22 diverge downwardly from the face of the sign 9 and their lower ends are curved inwardly as shown at 23 in Figs. 2 and 3. Fig. 2 shows the movable sign or curtain in its midway position and Fig. 3 illustrates the 25 curtain or movable sign completely covering the sign proper.

It will be noted in Fig. 2 the curtain is held away from the face of the sign 9 by virtue of the guide rollers 21 on the boom 11 engaging the 30 tracks 22. The same condition holds true when the guide rollers are in the upper parts of the tracks and the sign proper 9 is fully exposed. It likewise holds true as the movable sign or curtain moves downwardly from the position of Fig. 2 and practically all the time the curtain is moving. In this way the face of the sign 9 is never scratched or marred by the moving curtain.

As the guide rollers 21 move into the curved part 23 of the tracks 22 the movable sign or curtain is drawn inwardly and in the lowermost position of the movable sign as illustrated in Fig. 3 the curtain contacts the face of the sign. At this time the movable sign on the curtain is being displayed and the permanent sign 9 acts as an effective backing to insure against the sign buckling or being injured by high winds. While as heretofore stated the permanent sign 9 slopes inwardly toward the bottom the same result might be accomplished by having the permanent sign perpendicular and the angle of divergence of the track increased, the important thing being to have the face of the sign 9 substantially tangent to the circumference of the drum 13 and the track

22 diverging downwardly from the face of the sign.

A panel 25 may be provided over which the curtain may ride when in its retracted position.

5 The open space 6 heretofore mentioned provides ample room for the curtain to be withdrawn without interfering with any of the structural members.

The reciprocable or movable sign or curtain 10, 10 as heretofore stated, carries suitable advertising matter either painted or posted on its face. Another of the important aspects of the invention is that the face of the sign never contacts any moving or stationary part of the sign, thus it will 15 never be scratched or marred as would be the case where the curtain rolls up on a roller or is a continuous curtain passing over a plurality of rollers or drums.

It will be apparent from Fig. 1 that a very 20 realistic sign is provided. None of the moving or operating parts are exposed and a person will for a short period of time view the permanent sign on which for point of illustration the letters X Y Z are printed and they will then 25 view for a short period of time the sign on the movable curtain on which appears by way of example the letters A B C. The time of transition from the display of the permanent sign to the display of the sign on the reciprocating curtain is short thus increasing the effectiveness of 30 the sign.

Such changes in details of construction and arrangements of parts as might be made by one skilled in the art are to be considered as coming 35 within the spirit of the invention as set forth in the appended claims.

I claim:

1. A display sign having in combination, an upright permanent sign, a reciprocating curtain 40 bearing a sign, means for moving said reciprocating curtain so as to cause it to alternately cover and uncover said permanent sign, and means for holding said curtain away from said permanent sign while said curtain is moving and for holding said curtain in contact with said permanent sign when said permanent sign is covered.

2. A display sign having in combination, an upright permanent sign, a reciprocating curtain 45 bearing a sign, tracks for guiding said reciprocating curtain, means for moving said reciprocating curtain in relation to said tracks so as to cause it to alternately cover and uncover said permanent sign, and means for holding said curtain away from said permanent sign while said curtain is moving and for holding said curtain in contact with said permanent sign when said permanent sign is covered.

3. A display sign having in combination, an upright permanent sign, a reciprocating curtain

bearing a sign, tracks for guiding said reciprocating curtain, intwined curved portions on the lower ends of said tracks, and means for moving said reciprocating curtain in relation to said tracks so as to cause it to alternately cover and uncover said permanent sign, said tracks acting to hold said curtain away from said permanent sign while said curtain is moving and to hold said curtain in contact with said permanent sign when said permanent sign is covered.

4. A display sign having in combination, an upright permanent sign, a reciprocating curtain bearing a sign, a drum positioned above said permanent sign over which said curtain moves, the face of said permanent sign being substantially 15 tangent to the circumference of said drum, tracks for guiding said reciprocating curtain, said tracks having straight-away portions and intwined curved portions on their lower ends, said straight-away portions diverging downwardly from the 20 face of the sign, and means for moving said reciprocating curtain in relation to said tracks so as to cause it to alternately cover and uncover said permanent sign.

5. A display sign having in combination, an upright permanent sign, a reciprocating curtain bearing a sign, a boom extending along the forward edge of said curtain, guide rollers carried at either end of said boom, tracks with which said guide rollers cooperate, intwined curved portions 30 on the lower ends of said tracks, and means for moving said reciprocating curtain in relation to said tracks so as to cause it to alternately cover and uncover said permanent sign, said tracks acting to hold said curtain away from said permanent sign while said curtain is moving and to hold said curtain in contact with said permanent sign when said permanent sign is covered.

6. A display sign having in combination, an upright permanent sign, a reciprocating curtain bearing a sign, booms extending along the forward and rear edges of said curtain, a drum positioned above said permanent sign over which said curtain moves, guide rollers carried at either end of the boom extending along the forward 45 edge of said curtain, tracks with which said rollers cooperate, intwined curved portions on the lower ends of said tracks, sprocket chains secured to both ends of said booms, a driving sprocket to cause said sprocket chains to move 50 said reciprocating curtain so as to alternately cover and uncover said permanent sign, said tracks acting to hold said curtain away from said permanent sign while said curtain is moving and to hold said curtain in contact with said permanent sign when said permanent sign is covered and means for driving said sprocket first in one direction and then the other.

BENTON N. REAMER.
